United States Patent Office

Des. 226,281

Patented Feb. 6, 1973

226,281

TIME INDICATOR FOR COOKING

Leroy C. Lowe, P.O. Box 1241, Seattle, Wash. 98111

Filed June 24, 1971, Ser. No. 156,582

Term of patent 14 years

Int. Cl. D10—99

U.S. Cl. D52—6 B

FIG. 1 is a top view of a time indicator for cooking, showing my new design;

FIG. 2 is a front view thereof; and

FIG. 3 is an end view.

I claim:

The ornamental design for a time indicator for cooking, as shown.
